UNITED STATES PATENT OFFICE

117,776

DESIGN FOR A HANDKERCHIEF

Max Joseph Rosen, Brooklyn, N. Y.

Application October 21, 1939, Serial No. 87,784

Term of patent 3½ years

To all whom it may concern:

Be it known that I, Max Joseph Rosen, a citizen of the United States, residing at Brooklyn, New York, in the county of Kings and State of New York, have invented a new, original, and ornamental Design for a Handkerchief, of which the following is a specification, reference being had to the accompanying drawing, forming a part thereof.

The figure is a plan view of a handkerchief showing one fourth of the unit of my new design. The full lines of the drawing show one eighth of the design in detail, the other portions indicated in dotted lines being a repetition of the detailed illustrations arranged in proper relation thereto. The other three fourths of the unit are arranged about the common center, indicated by the dot and dash lines, in the same relationship as indicated in the illustrated one fourth.

I claim:

The ornamental design for a handkerchief, as shown and described.

MAX JOSEPH ROSEN.
